CLAIM

We claim the ornamental design for a beverage dispenser, as shown and described.

DESCRIPTION

FIG. 1 is a top perspective view of a beverage dispenser showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures depict portions of the beverage dispenser that form no part of the claimed design. For clarity, all text and icons appearing on various surfaces of the beverage dispenser are shown in dashed lines and form no part of the claimed design. The upper and lower broken lines extending horizontally across the beverage dispenser in FIG. 3 and the broken lines offset from the bottom peripheral edge of the beverage dispenser in FIG. 7 each illustrate a seam formed between adjacent components of the beverage dispenser. The above-referenced broken lines in FIGS. 3 and 7, respectively, form no part of the claimed design.
